(57) **CLAIM**

The ornamental design for a container-lid assembly, as shown and described.

DESCRIPTION

FIGS. 1 and 2 are perspective views of the container-lid assembly taken at different positions;

FIG. 3 is an upper plan view of the container-lid assembly of FIGS. 1 and 2;

FIG. 4 is a lateral elevational view of the container-lid assembly of FIGS. 1-3.

FIG. 5 is a similar view to that of FIG. 4, but illustrating the container-lid assembly in the exploded condition, in order to illustrate the ball surface portion projecting partially outwardly from the container of the present assembly; and, FIGS. 6-10 are similar views to those of FIGS. 1 and 5, respectively, but illustrating a second embodiment of the lid of the present container-lid assembly.

The broken line portions of the drawings are for illustrative purposes only, to show the environment of the present invention, and form no part of the claimed design.
